BUILDING CONSTRUCTION

Ewald Frank Techmer, Chicago, Ill.

Application February 5, 1932, Serial No. 591,068

2 Claims. (Cl. 72—101)

My invention relates to building construction, and includes among its objects and advantages the provision of an improved ground.

In the accompanying drawings:

5 Figure 1 is a perspective view in section showing a wall embodying my ground;

Figure 2 is a sectional view of a ground;

10 Figure 3 is a sectional view illustrating one method of fastening the ground to its supporting structure;

Figure 4 is an elevation of the structure shown in Figure 3;

15 Figure 5 is a different form of ground associated with a device for holding the ground while the latter is being fastened to its supporting structure;

Figure 6 is an elevation of the structure shown in Figure 5; and

20 Figure 7 is a sectional view of a carpet strip according to the invention.

In the embodiment selected to illustrate the invention, I make use of a floor 10 upon which a wall 12 is erected. The wall comprises a core 14 having plaster coats 16. The usual baseboards 18 and trim 20 and 22 are associated with the wall adjacent the floor 10. The above-described structure is old in the art and forms no part of my invention.

In Figure 1, I have illustrated grounds 24 and 26 as being incorporated in the wall to provide means to which the baseboards 18 and the trim 20 and 22 may be fastened. The grounds are formed from initially plastic material which, when cured, has nail receiving properties, thus permitting the baseboards and the trim to be nailed to the grounds. One formula by volume for making the ground is as follows:

	Per cent
Magnesium oxide	30
40 Wood or other filler	60
Asbestos	5
Clay	5

To this I add a magnesium chloride solution having a specific gravity of 22° Baumé. In lieu of the magnesium chloride solution, I may use magnesium sulphate having one per cent of sodium citrate added and the mass dissolved in water to make up a solution having a specific gravity of 28° Baumé.

45 I have found that various fillers may be employed such as straw, cork, and other fibrous materials. The ground is molded from the plastic composition and cured by drying. This ground may be severed by ordinary tools such as car-

penters' saws and wood chisels. At the same time, the ground embodies high fire resisting properties.

In Figure 2, I have shown an enlarged view of one of the grounds 24. The ground comprises a body 28 molded from the composition above described, and a reenforcing wrapper 30 comprising fabric or wire screen. The wrapper 30 is embedded in the top of the body 28 and also in its edges 32 and extends beyond the edges for providing flaps 34.

These flaps function as anchors for the ground, as illustrated in Figure 1. In other words, the flaps are fastened to the core 10 and embedded in the plaster 16, thus firmly anchoring the ground in place. It will be noted that the edges 32 are inclined so that the angle between the edges and the flaps 34, when the latter are fastened to the core 10, define an obtuse angle. This permits the plaster to be easily worked against the ground. Thus, the ground will be firmly anchored in the plaster when the latter has hardened. At the same time, such an angle makes it easy for the plasterer to finish the plaster coat flush with the top or exposed surface of the ground. A strip 36 is embedded in the base of the ground, as shown in Figure 2. This strip is made from the same material as the wrapper 30.

25 In addition to providing anchor means for the ground, the wrapper reinforces the ground in such a way that nails may be driven into the ground close to its edges without cracking or chipping the ground. I have also found that additional reinforcing strips may be molded into the ground as well as around it.

30 The wrapper will, of course, be completely embedded in the plastic material during the molding of the ground, thus securely fastening the wrapper to the ground. This is also true of the strip 36. The latter cooperates with the wrapper 30 for reenforcing the ground and prevents warping of the ground during curing which might occur in the absence of the strip.

35 Referring again to Figure 1, it will be noted that the grounds 26 have a cross-sectional contour different from the grounds 24.

40 The lower edges of these grounds are arranged at right-angles to the top and bottom surfaces of the ground, and these edges are provided with grooves 38 for receiving "sticking" such as plaster 40. The bases of the grounds 26 are depressed, as at 42, for receiving sticking. These grounds have a single flap 44 which functions in the same way as the flaps 34. It will be noted 45

that the sticking 40 ties the lower edges of the grounds to the floor 10, and that the sticking in the grooves 38 provides effective resistance against movement of the ground away from the core 14. The sticking in the depressions 42 effectively hold the grounds against shifting in an upward direction, while the flaps 44 firmly hold the ground against downward movement.

In Figures 3 and 4, I have illustrated one method of sticking the grounds to the unfinished wall preparatory to plastering. The base of the ground is covered with sticking 46 and is pressed against the wall structure 48. The flaps are flattened against the face of the wall structure and attached thereto by small batches of sticking 50. The sticking 50 provides tentative anchorage for the ground until such time as the plaster coats may be applied.

Referring to Figures 5 and 6, I have shown a device which may be employed for mounting the grounds upon the wall structure. I have illustrated a ground 52, rectangular in cross-section, as having recesses 54 in its edges. These recesses receive beads 56 carried by resilient members 58 fastened to a body 60 associated with a straight edge 62. The members 58 grip the ground and hold it perfectly straight. Thus, a ground may be assembled with this device, provided with a necessary amount of sticking, and pressed against the wall structure and tentatively fastened thereto while held in a perfectly straight condition and in proper alignment with the wall.

A surplus of sticking may be applied to the ground, which surplus provides compensation for the usual irregularities in the wall structure. In other words, the ground, after being provided with sticking, is pressed firmly against the wall to a position where the top surface will define the thickness of the plaster to be applied, and in being thus positioned, squeezing out the surplus sticking. The members 58 are sufficiently flexible to permit the holding device to be easily disassembled from the ground after it has been fastened to the wall.

In wall structures where the irregularities are of such magnitude that a ground of given depth may be too thin for certain portions of the wall and too great at other portions, I have found that grounds of different dimensions may be associated with the device illustrated in Figure 5 to the end that a perfectly straight surface is provided for the plaster. In other words, the exposed surface of the grounds will always bear against the body 60. This may easily be accomplished by molding the recesses 54 in the edges of the grounds at the same distance from the exposed surface.

In Figure 7, I have illustrated a carpet strip 64 constructed in accordance with my invention. This strip is provided with a reenforcing wrapper 66 having one flap 68 which may be fastened to the wall structure. Sticking 70 fastens the carpet strip to the floor 72. Should additional anchorage be desired, I provide openings 74 in the floor for receiving anchors 76 molded into the carpet strip. The hole 74 is filled with the sticking 70, thereby firmly securing the anchor 76.

Grounds constructed according to my inven-

tion are not only reenforced against chipping or cracking when nails or screws are forced therein, but are also reenforced against breaking into pieces. Furthermore, should a ground be accidentally broken, the pieces will be tied together by reason of the reinforcements. The construction also permits the manufacture of grounds relatively small in cross-sectional area, thereby providing a construction which may be easily bent into perfect alignment should any warpage occur. The ground is easily fastened to metal lath by simply applying plaster to the lath and anchoring the ground therein. This eliminates the necessity for wiring the ground to the lath.

It will be understood that the ground may be located in different places in the wall structure. The ground may also be positioned vertically at any desired angle. All the different types may be provided with anchors such as that shown at 76 in Figure 7. When so constructed, the ground may be associated with cement or brick walls. Ordinarily, sticking will suffice for fastening the ground to brick surfaces, but in cases where the ground must support heavy loads I have found that anchors 76 may be employed to advantage.

Without further elaboration the foregoing will so fully explain my invention that others may, by applying current knowledge, readily adapt the same for use under various conditions of service.

I claim:

1. In a building wall, a supporting floor, a core erected thereon, an upper ground and a lower ground, said lower ground having one edge provided with a depression and positioned adjacent the floor, a binding material between said edge and the floor and between one side of the ground and said core, the opposite edge of the lower ground being inclined to define an angle of more than ninety degrees between itself and said core, a binding material between said upper ground and the core, the upper and lower edges of said upper ground converging in a direction away from said core so that the angles between said edges and the core exceed ninety degrees, and a plaster coating upon said core, said coating cooperating with said inclined edges to anchor the grounds.

2. In a building wall, a supporting floor, a core erected thereon, an upper ground and a lower ground, said lower ground having one edge provided with a depression and positioned adjacent the floor, a binding material between said edge and the floor and between one side of the ground and said core, the opposite edge of the lower ground being inclined to define an angle of more than ninety degrees between itself and said core, a binding material between said upper ground and the core, the upper and lower edges of said upper ground converging in a direction away from said core so that the angles between said edges and the core exceed ninety degrees, a plaster coating upon said core, said coating cooperating with said inclined edges to anchor the grounds, and anchor means attached to said grounds and embedded in said plaster adjacent said core.

EWALD F. TECHMER.
